STEP STOOL

Earl F. Hamilton, Columbus, Ind., assignor to Hamilton Cosco, Inc., Columbus, Ind., a corporation of Indiana

Filed Mar. 30, 1959, Ser. No. 55,230

Term of patent 14 years

(Cl. D15—8)

Fig. 1.

Fig. 2.

Fig. 3.

Fig. 4.

FIG. 1 is a front elevation of a step stool showing my new design;

FIG. 2 is a side elevation thereof;

FIG. 3 is a plan view thereof; and

FIG. 4 is a perspective view thereof with the seat in retracted position.

The dominant features of my design reside in those portions shown in full lines on the drawing.

I claim:

The ornamental design for a step stool, as shown and described.
